INSULATED FLANGED WHEEL

Henry H. Talboys, deceased, late of Milwaukee, Wis., by
Doris Chisholm Talboys, executrix, Milwaukee, Wis.,
assignor to Nordberg Manufacturing Company, Milwaukee, Wis.

Filed June 2, 1961, Ser. No. 114,560

2 Claims. (Cl. 295—1)

This invention relates to an insulated railroad wheel of the type commonly used on railroad track working equipment. This application is a continuation-in-part of copending application, Serial No. 29,619, filed May 17, 1960, and now abandoned.

One purpose of this invention is a railroad wheel of the type described having a nonconductive insulating plastic annulus between the outer rim of the wheel and the inner hub.

Another purpose is an insulated wheel structure, suitable for use on railroads or the like, in which the insulating material is sufficiently strong to support the machine or car.

Another purpose is a wheel of the type described having improved means for providing both an axial and a circumferential interlock between the metal parts of the wheel.

Another purpose is an insulated railroad wheel of the type described in which a plastic annulus forms the insulation between the hub and the rim of the wheel, the invention further including a means for compensating for shrinkage upon solidification of the plastic annulus.

Another purpose is an improved method of forming an insulated railroad wheel of the type described.

Other purpose will appear in the ensuing specification, drawings and claims.

The invention is illustrated diagrammatically in the following drawings wherein:

FIGURE 1 is an end view of one form of insulated railroad wheel,

FIGURE 2 is a section along plane 2—2 of FIGURE 1,

FIGURE 3 is an end view taken along plane 3—3 of FIGURE 2,

FIGURE 4 is a side view of the wheel hub shown in FIGURES 1—3,

FIGURE 5 is an end view of the wheel rim shown in FIGURES 1 and 2,

FIGURE 6 is a section along plane 6—6 of FIGURE 5,

FIGURE 7 is an end view of a second form of insulated railroad wheel, and

FIGURE 8 is a section along plane 8—8 of FIGURE 7.

Track working equipment may be used on a section of railroad line while the line is in operation. It is therefore necessary that some means be provided on the track equipment to prevent the railroad signaling system from being operated. If conventional railroad wheels are used on the track equipment, the metal wheels and axle form a short circuit between opposite rails and hence operate the signals. Accordingly, insulating means are provided on the wheels to prevent a short circuit between the rails. It has been the practice in wheel structures of this general type to use an expensive bolt connection between the inner and outer wheel sections with pressed fiber for

2

insulation. Previously, there was used a rubber layer between the inner and outer wheel sections. Such a rubber layer was unsatisfactory as it deteriorated. Also it did not provide sufficient compressive strength and furthermore was to some extent resilient, giving a bouncy effect to the track equipment, which is undesirable.

In FIGURE 1, a metal rim 10 may have a flange 12, as conventional, which extends around the periphery of the wheel. Flanged wheels are normal on all railroad equipment and do not need extensive discussion. The rim 10 may be generally cylindrical in form and may include an enlarged internal bore 14 which may have a plurality of equally spaced, although they may be otherwise, generally circumferentially extending lugs 16. The lugs 16, which preferably are continuous, are separated by spaces 18 which may have an axial length approximating the axial length of the lugs 16.

Positioned within the bore 14 of the rim is a metal hub 20 which has an outer diameter less than the diameter of the bore, these diameters being measured at the farthest extent of the lugs. The outer surface of the hub 20 may have a plurality of lugs 22, which may be equally spaced or otherwise. The configuration of the outer surface of the hub and inner surface of the rim and the placement of these two members is such that the cavity or annulus defined therebetween preferably has a generally constant radial thickness. In other words, the lugs on the rim and hub are staggered so that the radial thickness of the annulus between the rim and hub is generally constant to provide an equal stress pattern. It is particularly advantageous to stagger the lugs on the rim and hub as this provides a strong and secure axial interlock. The hub is completed by an internal bore 24 which is used to mount the wheel on the axle.

In order to provide a circumferential interlock or to prevent circumferential movement between the rim and the hub, a plurality of generally equally spaced, although they may be otherwise, axially extending grooves 26 may be formed in the outer surface of the hub. In a like manner, a plurality of similar grooves may be formed in the internal surface of the rim, as at 28. When securing the hub and rim together, the grooves 26 may be placed in opposition to the grooves 28 or they may be staggered. The grooves 26 and 28 may be generally triangular in form, as shown in the drawings, or they may be otherwise. For example, they may be square, round, elliptical, etc. Instead of having grooves in both the rim and hub, a groove in one and a projection in the other may be provided, or projections in both may be provided. The particular form of the circumferential interlock is not important.

The particular form of the lug on both the rim and the hub may vary. As shown in the drawings, the lugs or teeth on the internal surface of the rim include a crest 30 and slanted side walls 32 and 34. This may vary. For example, these side walls could be straight, curved, arcuate or otherwise. What is important is to have a generally continuous lug which has sufficient thickness to provide a strong interlock with the hub. The same is true with the lugs formed on the outer surface of the hub.

The cavity defined between the rim and hub may be filled with a suitable plastic material. Polyurethane is a suitable plastic as it is sufficiently rigid and has sufficient compressive strength. In addition it provides high shear

strength which is important. One suitable type of polyurethane is that sold by Du Pont Company under the trademark "Adiprene" with a compound number of L-100.

FIGURE 7 shows a further form of the invention including a rim 36 having a flange 38, as described before. The rim 36 is somewhat cylindrical in form and includes an internal bore 40 within which is mounted a hub 42. Both the rim and the hub are metal, as described before, and the outer diameter of the hub is less than the internal diameter of the rim to define a cavity 44. The hub may be completed by a generally central bore 46 having a key-way 48, the bore 46 providing a means for mounting the wheel on the axle of the car.

In order to provide an axial interlock between the rim and the hub, the outer surface of the hub may have a gradually decreasing diameter from a point generally adjacent the center of the cavity 44 toward the opposite sides. In a like manner, the internal diameter of the rim may gradually increase from a point generally adjacent the center toward the outside. In other words, the thickness of the cavity 44 gradually increases from a point generally adjacent the center of the cavity towards the outside. It is also within the scope of the invention to provide an annulus or cavity in which the thickness gradually decreases from a point adjacent the center towards the outside. In this case, there would be a reverse taper on both the rim and the hub. Preferably, the shape of the cavity is as shown. To further provide an axial interlock, a circumferentially extending groove 50 may be formed in the outer surface of the hub adjacent the center and a similar circumferentially extending groove 52 adjacent the center of the internal surface of the rim. These grooves may be aligned, as shown in FIGURE 8, or they may be otherwise.

To provide a circumferential interlock for the wheel shown in FIGURES 7 and 8, a plurality of circumferentially spaced grooves 54 may be formed in the internal surface of the rim and similar grooves 56 in the outer surface of the hub. These grooves may take any form and they may be aligned, as shown in FIGURE 7, or they may be otherwise.

In both forms of the invention shown herein, the cavity or annulus defined between the rim and the hub is filled with a plastic, which is preferably polyurethane. This particular plastic has sufficient strength to withstand the heavy load of the track equipment. In addition, polyurethane provides resistance to shocks. It is sufficiently rigid so that the track equipment will have a firm and steady support. The polyurethane, in liquid form, is poured into the cavity defined between the rim and hub and then is allowed to cure. Polyurethane may be oven cured in three hours at a temperature of between 180-215 degrees F. Under ambient conditions, polyurethane may cure in about three weeks.

Polyurethane may shrink to a small extent, about 1.7 percent, upon solidification and curing. To compensate for this shrinkage, a plurality of holes 58 may be drilled in the plastic annulus 60. The holes are drilled prior to curing of the polyurethane, but after it has set sufficiently to be worked. Pins 62, which are oversized, are then placed in the holes 58. Preferably, the pins are formed of an electrically non-conductive material, for example nylon or the like.

In forming the wheel of FIGURES 7 and 8, after the polyurethane has set to a point where it can be drilled, holes of a certain size are formed. Then nylon pins, which may, for example, be $\frac{1}{2}$ inch oversize in diameter, are placed in the holes. The polyurethane is then allowed to cure for a period of about three weeks under normal conditions. As the polyurethane cures, it shrinks. However, as polyurethane has plastic memory, and as the pins, nylon or otherwise, were initially oversized, the shrinkage will be compensated for and the pins and annulus will be firm.

Considering the particular form of cavity in FIGURES 7 and 8, shrinkage of the polyurethane provides a self-

locking effect. As it shrinks and draws back, it merely moves toward the center of the cavity and hence will always remain in firm contact with the tapered outer walls of the rim and hub.

5 The use, operation and function of the invention are as follows:

Shown and described herein is an improvement in insulated wheels for railroad track or the like. The wheel includes an outer metal rim and an inner metal hub, the outer diameter of the hub being less than the diameter of the rim to define an annular cavity therebetween. The cavity is filled with a plastic, preferably polyurethane, which has sufficient compressive and shear strength to adequately support the track working equipment. The polyurethane may include suitable fibers or fillers to add strength and to increase the viscosity during pouring. The fibers or fillers also are effective to reduce shrinkage.

In order to provide both a circumferential and an axial interlock between the rim and the hub, a plurality of generally circumferentially extending lugs or teeth may be provided which are axially spaced on the outer surface of the hub and the internal surface of the rim. Preferably, the lugs are positioned such that there is a cavity of constant thickness between the rim and hub to form a tortuous interlock.

In the form shown in FIGURES 7 and 8, the outer surface of the hub and the internal surface of the rim have been tapered such that the thickness of the cavity gradually increases from a point adjacent the center toward the outside. When the polyurethane shrinks upon solidification and curing, it will merely move toward the center and still provide continuous contact between the rim and hub and hence continuous support.

In order to compensate for the shrinkage upon solidification and curing of the polyurethane, a plurality of holes is provided in the polyurethane and oversized pins positioned within these holes. The pins are oversized and hence as the polyurethane shrinks, the plastic memory quality of the polyurethane will allow it to remain firmly around the pins. The oversized pins are effective to compensate for the shrinkage of the polyurethane. Although the oversized pins are shown in connection with the form of the invention of FIGURES 7 and 8, this concept can also be used with the wheel of FIGURES 1-6.

There are many variations for the particular structure shown herein. For example, axially extending grooves are shown in the internal surface of the rim and the outer surface of the hub in both forms of the invention for providing a circumferential interlock. Projections in both the rim and the hub may be used or a projection in one and a groove in the surface of the other may be used. The grooves or projections may be aligned, as shown herein, or they may be staggered. Either form is satisfactory.

Whereas the preferred form of the invention has been shown and described herein, it should be realized there are many modifications, substitutions and alterations thereto within the scope of the following claims.

60 I claim:

1. An insulated wheel for use on railroad track or the like including a cylindrical metal rim having a generally continuous flange around its outer periphery and an enlarged internal bore, a metal hub positioned within the bore and having an outer diameter less than the diameter of the bore, the outer surface of the hub and the inner surface of the rim having generally equally and axially spaced circumferentially extending lugs, the outer diameter of the lugs on the hub surface being less than the inner diameter of the lugs on the rim surface, the lugs on the hub surface and the lugs on the rim surface being staggered and spaced, relative to each other, such that the cavity between the inner surface of the rim and the outer surface of the hub has a generally constant radial thickness throughout, generally circumferentially

spaced axially extending grooves in the outer surface of the hub and the inner surface of the rim, said axially extending grooves being in radial alignment, and a generally rigid plastic annulus filling the cavity between the rim and hub and providing an interlock therebetween.

2. The structure of claim 1 further characterized in that said plastic annulus includes polyurethane.
